UNITED STATES PATENT OFFICE.

JOHN RIDDELL AND GEORGE B. PAINTER, OF SCHENECTADY, NEW YORK,
ASSIGNORS TO GENERAL ELECTRIC COMPANY, A CORPORATION OF NEW
YORK.

ELECTRIC ROCK-DRILL.

No. 852,680.

Specification of Letters Patent.

Patented May 7, 1907.

Application filed September 19, 1902. Renewed October 29, 1906. Serial No. 341,129.

To all whom it may concern:

Be it known that we, JOHN RIDDELL and GEORGE B. PAINTER, citizens of the United States, residing at Schenectady, county of 5 Schenectady, State of New York, have invented certain new and useful Improvements in Electric Rock-Drills, of which the following is a specification.

This invention relates to electrically operated mechanism for drilling rock and its object is to improve the parts which hold, rotate and feed the drill.

The invention relates more particularly to such an electric rock-drill as is set forth in the 15 patent to George W. Pickett, No. 632,658, dated September 5, 1899, although it is applicable to any type of rock-drill in which a hammer blow is delivered upon the head of the drill.

20 In mechanism heretofore proposed for holding and turning the drill, the tool has been held more or less rigidly in the clutch or head, so that if in operating the drill the feeding mechanism did not happen to carry the 25 drill-point to the bottom of the hole, the blow delivered by the hammer on the head of the drill would be transferred to the clutch itself, and back through it to the actuating mechanism. It is evident that a clutch or drill-30 head which would leave the drill perfectly free at the instant the blow was struck would relieve the apparatus from this objectionable feature; and it is the object of our invention to accomplish this result.

35 A further object is to enable a large drill to be readily inserted and removed from the holder.

The invention consists in a drill-head or clutch comprising jaws or dogs which automatically grip the drill and hold it firmly 40 while it is being retracted and partially rotated but which let go the drill when it is advanced and thus leave it perfectly free to transmit the blow of the hammer to the cutting edge and the material which is being operated on.

The invention also consists in certain details of construction hereinafter set forth.

In the accompanying drawings, Figure 1 is 50 a side elevation of an electric rock-drill of the Pickett type equipped with our improved drill-head; Fig. 2 is a sectional elevation of the drill-head; Fig. 3 is a cross-section thereof on the line 3 3 of Fig. 2; Fig. 4 is a cross-

section thereof on the line 4 4, Fig. 2; Fig. 5 55 is a longitudinal section of the portion thereof on the line 5 5, Fig. 2; Fig. 6 is a perspective view of one of the gripping dogs; Fig. 7 is a perspective view of the feather which effects the turning of the drill-head; Fig. 8 is a 60 sectional elevation showing the manner of removing a drill; Fig. 9 is a cross-section of Fig. 8 on the line 9 9, and Fig. 10 is a perspective view of the spring catch for the pin 65 on which the fork turns.

An electric rock-drill of this type consists of three general parts, viz., a drill mechanism comprising a drill supported in a suitable holder so that it can be struck a rapid series of blows by a hammer, an electric motor, and 70 mechanism interposed between the two by means of which the rotation of the armature of the motor actuates the hammer and at the same time retracts and turns the drill after each blow. The general appearance of such 75 a drill is shown in Fig. 1, in which it is arranged for drilling a hole vertically downward. It will be understood, however, that it can be adjusted to work in any direction.

The electric motor and operating mechanism which actuate the hammer 1 are not shown, since they form no part of our invention. They are inclosed in a casing 2 which serves as the main frame of the machine. This casing is in turn supported by a frame 80 or bed-piece 3 upon which it has a longitudinal movement controlled by a screw 4 attached to the frame 3 and working in a nut 5 secured to the frame 2, so that by turning the screw by means of the crank 6 the casing 2 85 and with it the operating mechanism may be advanced or retracted by the operator at 90 will. The frame 3 is provided with a lug or trunnion 7 and with adjustable lugs 8 so that it may be clamped to a column or fixed directly to the walls of a shaft or tunnel in any 95 desired position in the usual way.

Secured to the casing 2 is a holder 9 through which the drill 10 passes longitudinally, the head and point of the drill projecting above and below the holder as shown. Inside the holder and concentric with the drill is a clutch by means of which the drill is retracted and partially turned between the blows of the hammer. This clutch comprises a sleeve 11 having an easy fit on the shank of the drill and provided with a circumferential groove 12 with which engages a 100 105

fork 13 connected by a rod 14 with a tail-piece 15 constituting a part of the actuating mechanism, as fully set forth in the Pickett patent above referred to. The fork 13 is pivoted at its rear end on a pin 16 so that the longitudinal reciprocation of the rod 14 will oscillate the fork up and down and thereby lift and lower the sleeve 11.

In order that the lifting movement of the sleeve may be communicated to the drill, we provide a plurality of dogs 17 arranged radially around the drill in an enlarged portion 11' of the sleeve and capable of movement lengthwise of the sleeve. The dogs are guided and held in their relative positions by means of radial slots 18 in the lower end of the enlargement 11'. The under side of each dog has a V-shaped notch forming teeth 17' 17², having inclined surfaces. The upper end of the sleeve 11 is conically countersunk to engage with the inner teeth 17'. That portion of the head adjacent to the conical upper portion of the sleeve is beveled to enter said notches also, and engage with the outer teeth 17², as clearly shown in Fig. 2.

We prefer to provide means for exerting a downward pressure on the dogs in order to insure their biting the drill. This may consist of one or more blocks of rubber 19 placed above said dogs, either with or without an interposed washer 20, and restrained from upward movement by means of a cap 21 suitably secured to the upper end of the enlargement 11', as by means of the pins 22 and the bayonet-joint notches 23.

The partial rotation of the sleeve between the blows of the hammer is effected by means of a stationary feather 24 adapted to slide longitudinally and rotate in a socket 25 projecting from the holder 9 and urged yielding inward by a spring 26. The feather enters a zigzag groove in the outer surface of the sleeve 11. Said groove comprises alternate longitudinal grooves 27 and helical grooves 28, the former intercepting the latter at points not far from their upper ends and the latter intercepting the former at points not far from their lower ends, as clearly shown in Figs. 2 and 8. Each groove is deeper at its outer end and slopes gradually upward to its other end where it intersects the other groove, as clearly shown in Fig. 5. The result is that at the points of intersection there is a slight shoulder 29.

55 The operation of the device is as follows: When the sleeve 11 is retracted by the fork 13 its upper end lifts the dogs 17 away from the beveled stationary surface of the holder 9 and by reason of its conical inner surface acting on the inner teeth 17' draws the dogs tightly against the drill which is thus firmly clutched and retracted with the sleeve 11. This action is facilitated by the pressure of the rubber 19 on the upper ends of the dogs, which tends to force them into the sleeve and

against the drill. During this upward movement of the sleeve the feather 24 is in engagement with one of the helical grooves 28, and as the sleeve rises past the stationary feather it is given a partial rotation until the feather drops over into the next longitudinal groove 27, after which the upward travel of the sleeve is without angular movement. When the sleeve descends the feather is in engagement with the longitudinal groove and is prevented from re-entering the helical groove in which it formerly lay by reason of the shoulder 29 at the junction of said two grooves. The sleeve is therefore caused to descend without any angular movement until, as it approaches its lowest point of movement, the feather drops into the next helical portion of the groove and the sleeve is thus given a slight retrograde angular movement as it reaches the lower end of its travel. Just before the sleeve comes to rest, the outer teeth 17² of the dogs slide down upon the stationary beveled portion 30 of the holder, the dogs being thereby withdrawn from the drill, which is thus left entirely free in the clutch so that the blow of the hammer will not be imparted to any portion of the mechanism.

A valuable feature of our invention is the facility with which the drill can be changed. In order to effect this, the pin 16 is drawn out, as shown in Fig. 9, being quickly released by disengaging the spring-arm 31 from the groove 32 in said pin. A second groove 33, with which said arm engages, holds the pin in the position shown in Fig. 9, so that it will not be lost. The fork 13 is disengaged from the groove 12 in the sleeve and dropped into an upright position, as shown in Fig. 8. The feather 24 is drawn back out of engagement with the groove in the sleeve, and is locked in this position, preferably by giving it a quarter turn, so that the transverse pin 34 will be caught on the projection 35 on the cap 36. The cap 21 is then loosened to relieve the pressure of the spring 19 on the dogs, and relax their grip on the drill. This leaves the sleeve free to be lifted out of the holder, as shown in Fig. 8. The drill can then be easily drawn up through the holder 9. By making the shanks of the drills of substantially uniform size, so that the same set of dogs can be used, the cutting points may be made of any size capable of passing through the holder. This is of especial usefulness in drilling deep holes, which are begun with a large drill, but at certain depths are continued with smaller and smaller drills. With our device, the drills can be readily and quickly changed without disturbing the machine.

What we claim as new and desire to secure by Letters Patent of the United States, is,--

1. An electric rock-drill provided with means for clutching the drill, means for retracting and turning and also advancing it,

- and means for unclutching it when advanced, so that it will be entirely free when struck.
2. In a rock-drill, a reciprocating clutch provided with dogs, and means for causing said dogs to bite the drill when the clutch is retracted, and means for causing said dogs to let go when the drill has been advanced and prior to being struck.
3. In a rock-drill, a reciprocating clutch provided with radially movable dogs, and means for moving said dogs inward when the clutch is retracted and means for moving them outward when the clutch has been advanced and prior to the drill being struck.
4. In a rock-drill, a plurality of radially movable dogs, each having oppositely inclined surfaces, a relatively movable sleeve having an inclined surface adapted to co-operate with the surfaces of the dogs inclined in one direction, and a stationary holder for said sleeve having a beveled portion to engage the opposite inclined surfaces on the dogs.
5. In a rock-drill, a sleeve having a conically countersunk upper end, a cupped enlargement on said sleeve having radial slots, dogs fitted to move radially and longitudinally in said slots and provided with V-shaped notches engaging the end of the sleeve, and means for pressing said dogs into said sleeve.
6. In a rock-drill, a sleeve having a conically countersunk upper end, a cupped enlargement on said sleeve having radial slots, dogs fitted to move radially and longitudinally in said slots, and provided with inclined surfaces engaging the sleeve, and one or more rubber blocks resting on said dogs.
7. In a rock-drill, a sleeve having a conically countersunk upper end, a cupped enlargement on said sleeve having radial slots, dogs fitted to move radially and longitudinally in said slots, and provided with inclined surfaces engaging the sleeve, one or more rubber blocks resting on said dogs, and a cap secured to said enlargement and confining said blocks.
8. In a rock-drill, a reciprocating sleeve provided with alternate longitudinal and helical grooves intersecting one another at points near their ends, said grooves being deeper at one end than at the other, and a spring-pressed feather engaging with said grooves.
9. In a rock-drill, a reciprocating sleeve provided with alternate longitudinal and helical grooves intersecting one another at points near their ends, said grooves being deeper at one end than at the other, and one deeper than the other at the point of intersection, and a spring-pressed feather engaging said grooves.
10. In a rock-drill, the combination with a holder, of a sleeve-clutch having a circumferential groove, a fork engaging with said groove, a pin on which said fork is pivoted, having grooves at two points, and a spring-arm to enter said grooves and lock the pin both when in place and when withdrawn from the fork.

In witness whereof we have hereunto set our hands this 17th day of September, 1902.

JOHN RIDDELL.
GEORGE B. PAINTER.
